UNITED STATES PATENT OFFICE.

UDOLPHO H. ODELL, OF DAYTON, OHIO.

MIDDLELINGS-PURIFIER.

SPECIFICATION forming part of Letters Patent No. 350,385, dated October 5, 1886.

Application filed March 25, 1886. Serial No. 196,553. (No model.)

To all whom it may concern:

Be it known that I, UDOLPHO H. ODELL, a resident of Dayton, in the county of Montgomery and State of Ohio, have invented certain new and useful Improvements in Middlelings-Purifiers, of which the following is a specification.

My invention relates to that class of middlelings-purifiers which employs either a suction or force blast to assist in purification. I have illustrated the application as employing a suction-blast fan; but I do not wish to limit myself to the use of the suction-blast, as my invention is equally adapted to be used in any well-known form of purifying-blast.

One of the principal objects of my invention is to provide suitable means to keep the screen-cloth clean, or to prevent the fluff from being caught in the mesh of the cloth of a purifier or separator.

Another object of my invention is, in addition to cleaning the cloth, to present the middlelings or stuff operated upon by the riddle to the action of the air-blast, so as to carry off the fluffy matters, all of which will be fully set forth in the description of the accompanying drawings, making a part of this specification, in which—

Figure 1 represents my improvement attached to the case of a middlelings-purifier. Fig. 2 is a longitudinal vertical central section of the same. Fig. 3 is a top plan view of the riddle-cleaning device.

A represents the frame of the purifier; B, the blast-chamber; C, the fan; D the riddle-frame; E, openings for the admission of air into the purifying-chamber; F, feed-opening; G, feed-spout; H, cross-arms of the riddle-frame; I, an eccentric for shaking the riddle.

K represents spring shaker-bars, the ends of which are attached to the frame of the purifier.

L represents a bolt attaching the spring-bars to the riddle. These bars spring enough to allow the riddle to have a reciprocating motion.

I do not wish to limit myself to the method herein shown of suspending the riddle-frame, as any well-known form may be employed in lieu of the devices herein shown and accomplish the principal purposes of my invention.

50 a represents sprocket-wheels. b represents a sprocket-chain traveling thereon.

c represents the cloth attached to the under side of the riddle-frame.

d represents a series of stationary slats or arms attached to a rectangular frame, e. These slats can be made adjustable, if desired. The frame e is supported in the frame of the machine a sufficient distance from and preferably under the riddle-frame. The sprocket-chain or endless belt is preferably carried around the rails of the frame e.

h represents a cross bar rigidly attached to the sprocket-chain or endless belt, and is carried around over the sprocket-wheels and under the riddle-frame, as shown in Fig. 2.

i represents a series of balls, preferably made of rubber, attached to a string, which is preferably made of rawhide or other tenacious substance. The strings are secured to the bar h and the balls at the free ends of the strings o. As the bar h is drawn across, the balls strike the slats d and rebound up and strike the cloth c and drop down and strike the ends of a succeeding rail d, which again causes the ball to rebound and strike against the cloth. Thus a continual intermittent striking of the balls against the cloth is obtained as the bar h is drawn across under the riddle-frame.

I do not wish to limit myself to the use of balls, as any weighted matter attached to the free end of a flexible cord which is secured to the bar h may be used to secure the knocking or striking action against the cloth as the bar h is drawn across under the riddle-frame. This action of the balls is very important, as the sharp blow beats or knocks the fluff out of the cloth should any be lodged therein; but these knockers also perform a more important function. The blow striking against the cloth throws the middlelings or stuff resting on the screen up and subjects the stuff so elevated to the action of the air-blast, which carries off the fluff and in a great measure prevents it from settling into the meshes of the separating-cloth.

This device may be used with any known form of purifier, and it is much superior to the cloth-cleaners hitherto employed for this purpose.

The shape and form of the rails or stops d may be variously modified. I deem wooden slats set a sufficient distance apart to allow the air to pass up between them to be the cheapest

and best; but any arrangement or form of stops with air-spaces between them may be employed in lieu of the slats *d* here shown, the object being to furnish a movable obstacle, 5 against which the balls hit as they are dropped by gravity and rebound against the cloth, so as to throw the stuff up and subject it to the action of the air-blast.

Having described my invention, what I claim 10 as new is—

1. In a purifier, the combination, with an agitating-riddle having a separating-cloth, of the frame *e*, having a series of stops, *d*, an endless belt provided with a cross-bar, *h*, and 15 a series of flexible knockers attached to said bar, substantially as described.
2. In a purifier, the combination of a riddle,

an endless belt provided with a cross-bar, a series of knockers connected to said cross-bar, and a series of stops, substantially as de- 20 scribed.

3. In combination with the riddle of a purifier or separator, a series of slats, *d*, a traveling belt, and a series of rebounding knockers, *i*, arranged to travel between the riddle-cloth 25 and the slats, whereby the knockers are made to strike intermittently against the cloth, substantially as specified.

In testimony whereof I have hereunto set my hand.

UDOLPHO H. ODELL.
